JOHN C. RINGE, OF BRIDGEPORT, CONNECTICUT, ASSIGNOR TO THE SINGER MANUFACTURING COMPANY, A CORPORATION OF NEW JERSEY.

ROTARY TAKE-UP FOR SEWING-MACHINES.

1,292,064.

Specification of Letters Patent. Patented Jan. 21, 1919.

Application filed February 9, 1918. Serial No. 77,124.

To all whom it may concern:

Be it known that I, JOHN C. RINGE, a citizen of the United States, residing at Bridgeport, in the county of Fairfield and 5 State of Connecticut, have invented certain new and useful Improvements in Rotary Take-Ups for Sewing-Machines, of which the following is a specification, reference being had therein to the accompanying 10 drawings.

This invention relates to an improvement in rotary take-ups, and it has for its object to provide for the effective handling of an abnormally long length of needle thread in 15 conjunction with a rotary lock-stitch loop-taker performing two rotations for each reciprocation of the needle and each rotation of the take-up, as disclosed more fully in my application Serial No. 77,123 filed simultaneously herewith. In its preferred form, the take-up comprises the usual spaced rotary disks secured together by means of an intermediate spacing lug and having in one of said disks a marginal arcuate slot in 25 which works a relatively movable thread-engaging stud-pin carried by a vibratory lever which is fulcrumed upon said disk and is yoked to embrace a stationary controlling eccentric, whereby in the rotation of the take-up the stud-pin performs an accelerated movement in the thread-drawing semi-rotation of the take-up and a retarded movement to initial position in the thread-slacking semi-rotation.

30 The invention will be understood by reference to the accompanying drawings, in which Figure 1 is a front end elevation of a sewing machine embodying the present improvements, with the bed-plate in section. Fig. 2 is a sectional plan of the head of the bracket-arm with the parts carried thereby, and Fig. 3 is a plan view of the take-up, partly in section. Figs. 4 and 5 are perspective views, respectively, of the 35 take-up disks. Figs. 6 and 7 are front end views of the take-up in different operative positions in conjunction with the stitch-forming elements, the loop-taker being represented conventionally. Fig. 8 represents 40 in perspective the needle-actuating means with the controlling eccentric and its support detached. Fig. 9 represents in perspective the vibratory stud-pin carrying lever and its accessories, certain of which are de-

tached therefrom for purposes of illustration. 55

The sewing machine frame is of a well-known form, comprising the bed-plate 1 from which rises the hollow standard 2 carrying the overhanging tubular arm 3 terminating in the hollow head 4 which is formed in its outer portion with a circular recess embraced within the annular flange 5. Beneath the throat-plate 6 is sustained the 60 loop-taker comprising in the present instance the rotary hook 7 with loop-seizing beak 8 and carrying the thread-case 9 which in the present instance is of unusually large capacity to adapt the machine for operation in an abnormally long stitching period without renewal of the lower thread supply. 65

Coöperating with the loop-taker is the eye-pointed needle 10 carried by the reciprocating needle-bar 11 which is journaled in the bearing sleeve or bushing 12 and has 70 pivotally connected to its upper end by means of the screw 13 a boss at the lower end of the pitman 14 which is formed at its upper end with a strap embracing the crank-pin 15 upon the crank-disk 16 which 75 is in turn mounted upon the main-shaft 17 journaled in the bracket-arm 3.

The crank-pin 15 rigidly sustains at its forward end the crank-arm 18 which carries a boss 19 disposed concentrically with the 80 main-shaft 17. Secured upon the forward face of the boss 19 by means of screws 20 tapped therein is the primary take-up disk 21 which carries at one side of the center the outwardly inclined elongated spacing 85 lug 22 adjacent which is disposed the marginal arcuate slot 23 formed in the inner face of the disk with a surrounding countersunk recess 23'.

Secured upon the lug 22 by means of 90 screws 24 entering apertures 25 therein, is a second cutout disk or ring 26 formed with a central aperture 27 in its hub portion and upon its rearward face with a marginal 95 arcuate countersink 28 in register with the 100 countersink of the slot 23 of the primary take-up disk (Fig. 3).

Secured within the outer recess of the bracket-arm head is a transverse bridge-piece or support 29 which is formed with an 105 apertured boss 30 to which is secured by means of screws 31 the controlling eccentric 32 formed with a clearance aperture 33 for

the boss 19. Fitted upon the eccentric 32 is the suitably apertured slide-block 34 having its parallel opposite faces fitted to the adjacent side walls of the yoke 35 formed intermediate the ends of a vibratory lever 36 which has tapped into one end the reduced and threaded portion of the take-up stud 37 having a shouldered part passing through the slot 28 and its operative part or 10 head entering the registering countersinks 23' and 28 of the spaced take-up disks.

The lever 36 has formed in its opposite end an aperture 38 which is journaled upon the boss 39 of a screw-stud having its 15 threaded shank 40 tapped into a suitable aperture of the primary take-up disk and formed with an angular flange 41 affording a head for the same. The apertured end of the lever 36 is confined upon the stud 39 between the flange 41 and the head of a screw 20 42 tapped into a suitably threaded aperture of said stud.

The bracket-arm head has depending from the upper side of its cavity the oiling tube 25 43, which is well-known in this class of machines, the beveled lower end of this tube being in register with an oil groove 44 formed in the face of the eccentric-sustaining boss 30. The eccentric 32 is formed in the face 30 adjacent said boss with a lubricant cavity 45 which is entered by oil-distributing apertures 46 extending outwardly therefrom into the opposite ends of a peripheral oil-distributing groove 47 adapted to lead lubricant to 35 the journal of the slide-block 34.

The cavity 45 is preferably packed with wicking or other lubricant absorbing material. Through the tube 43 and duct 44 lubricant is readily introduced into the cavity 40 45 from which it is distributed upon the outer face of the stationary controlling eccentric by means of the aperture 46 and distributing groove 47.

In the operation of the stitch-forming mechanism, as the needle rises after a descent to extreme lower position, the needle-thread is seized by the point of the loop-taker beak 8, the take-up at this time giving slack, as represented in Fig. 6, to permit the 45 rapid distention of a needle-thread loop in the casting operation performed by the loop-taker. As the loop-taking member completes slightly more than a semi-rotation (Fig. 1) from loop-seizing position the loop-drawing action of the take-up begins, the 50 needle-thread being forcibly engaged by the take-up lug 22 and the stud-pin 37 which, during its thread-drawing engagement with the thread, performs an accelerated movement up to its stitch-setting position (represented in Fig. 7).

The needle having risen to its highest position and begun its descent, at the position 55 represented in Fig. 7, the needle-eye is slightly above the work, and upon the fur-

ther rotation of the take-up, the thread is slackened so that as it passes through the work there is no danger of cutting or otherwise injuring the thread. The needle-thread above the work remains slackened through 70 a period beginning with the position of the take-up represented in Fig. 7, including that of Fig. 6, and extending to substantially that of Fig. 1.

While the component elements of the present improvement are disclosed herein in the form and arrangement which are preferred, it is evident that the mechanism may be materially modified in either of these aspects 75 within the scope of the invention.

Having thus set-forth the nature of the invention, what I claim herein is:—

1. A sewing machine take-up comprising a pair of spaced rotary disks, a plurality of 80 relatively movable thread-engaging elements operatively connected to and rotating with and having operative portions intermediate said disks, and means including a controlling stationary element for producing between said thread-engaging elements relative circumferential movements.

2. A sewing machine take-up comprising a pair of spaced rotary disks, an intermediate spacing lug connecting them together and affording a thread-engaging element, a 85 stud-pin rotating with and having on operative portion intermediate said disks and affording a second thread-engaging element, and means connected with said stud-pin and including a stationary controlling element 90 for imparting to the same to-and-fro circumferential movements.

3. A sewing machine take-up comprising a pair of spaced rotary disks, an intermediate spacing lug connecting them together 105 and affording a thread-engaging element, a stud-pin having an operative portion intermediate said disks and affording a second thread-engaging element, a fulcrum-pin carried by one of said disks, a lever mounted 110 upon said fulcrum-pin and carrying said stud-pin and formed intermediate the same with a yoke, and a stationary eccentric embraced by said yoke for imparting swinging movements to said lever.

4. In a sewing machine, in combination, a rotary shaft, an actuating crank-pin thereon, a reciprocating needle-bar carrying a needle, a pitman connection between said needle-bar and said crank-pin, a boss sustained by 120 said crank-pin in alinement with said shaft, a stationary eccentric apertured to afford clearance for said boss, a pair of spaced disks sustained by said boss and rotating with said shaft, relatively movable thread-engaging 125 elements rotating with and having operative portions intermediate said disks, and means, including a lever fulcrumed upon one of said disks and yoked to embrace said eccentric, for imparting to one of said thread-engaging 130

elements to-and-fro circumferential movements.

5. A sewing machine take-up comprising a pair of spaced rotary disks, an intermediate spacing lug connecting them together, a stud-pin having an operative thread-engaging portion intermediate said disks, a lever carrying said stud-pin and having a fulcrum movable with said disks, a stationary eccentric operatively connected with said lever and formed with an internal lubricant cavity communicating with the operative face of the same, a slide-block fitted 20 upon said eccentric and embraced by the yoke of said lever, and a supply duct leading to the lubricant cavity of said eccentric.
- 10 6. A sewing machine take-up comprising a pair of spaced rotary disks, an intermediate spacing lug connecting them together, a stud-pin having an operative thread-en-
- 15 6. A sewing machine take-up comprising a pair of spaced rotary disks, an intermediate spacing lug connecting them together, a stud-pin having an operative thread-en-

gaging portion intermediate said disks, a yoked lever carrying said stud-pin and having a fulcrum movable with said disks, a stationary eccentric operatively connected with said lever and formed with an internal lubricant cavity communicating with the operative face of the same, a slide-block fitted 25 upon said eccentric and embraced by the yoke of said lever, and a supply duct leading to the lubricant cavity of said eccentric.

In testimony whereof, I have signed my name to this specification, in the presence of 30 two subscribing witnesses.

JOHN C. RINGE.
